UNITED STATES PATENT OFFICE

WILLIAM A. GEIGER, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed February 13, 1928. Serial No. 254,011.

This invention relates to improvements in railway draft riggings.

In the art of railway draft riggings, it has long been known that the service demanded of draft gears is constantly increasing, due to the increase in size of individual cars, increased length of trains, and the more powerful locomotives. With the standard buff and draft travel of gears amounting on the average to $2\frac{3}{4}$ ", it has been found extremely difficult to properly absorb these heavier loads, particularly in buff. There is now arising a definite demand for draft gears having a longer stroke in order that the heavier buffing blow, particularly, may be more effectively cushioned and this must be accomplished without increase in train slack, which is extremely undesirable.

One object of my invention is to provide a railway draft rigging wherein provision is made for a long buffing stroke of the draft gear, while at the same time retaining the comparatively short and desirable draft stroke, to the end that the heavier buffing blows may be properly absorbed without increase in train slack.

A more specific object of my invention is to provide a combined friction shock absorbing device and yoke member such that proper alinement of the coupler and draft gear is maintained at all times and all danger of the coupler drooping or sagging or being tilted upwardly during coupling of cars, is eliminated.

Still more specifically, an object of my invention is to provide an integrally formed yoke and friction shell member so arranged that the yoke portion thereof will support the coupler in proper horizontal position in any operative condition of the draft rigging.

Other objects of the invention will more clearly appear from the description and claims hereinafter following.

In the drawings forming a part of this specification, Fig. 1 is a part vertical sectional view, part elevational view of a portion of a railway car showing my improvements in connection therewith. And Fig. 2 is a horizontal, longitudinal, sectional view

corresponding to the section line 2—2 of Fig. 1.

In said drawings, 10—10 denote the usual channel draft sills of a car underframe, said sills constituting continuations of the center sills in the particular embodiment illustrated. At their outer ends, said sills are united to the usual end sill 11, and the opening at the end of the sills is reinforced by an end buffer casting 12 which may be of any suitable or desired construction. The usual bolster is indicated at 13, the same having a center filler casting 14 which, in the instance shown, is provided with forwardly extended side arms 15—15 riveted to the sills and having flanges 16—16 at their front ends which provide the rear stops of the draft rigging. As clearly shown in Fig. 2, the filler casting 14 is suitably recessed so as to accommodate the rearward movements of the yoke member, 70 hereinafter described.

In carrying out my invention, I employ a combined yoke and friction shell member designated generally by the reference character A, and associate therewith suitable friction elements and spring resistance, one form of which will be described. A modern standard coupler is indicated at B, the same being operatively connected to the member A by the usual coupler key C, which is extended through alined slots in the coupler and member A and also through elongated slots 17—17. Said slots 17 are formed in reinforcing plates or castings 18 riveted to the sills A, as clearly shown in Fig. 2. As shown in the same figure, the coupler key C is so positioned, normally, in the slots 17, that it may have a much greater buff movement than draft movement.

The front stop and follower means of the gear proper is obtained through a second key D which passes transversely through alined slots 19 in the castings 18 and slots 20, in the member A. Said key D normally occupies a forward position in all of said slots, as shown in Fig. 2 and is adapted for the full buff movement in the slots 19 and for the desired shorter draft movement with reference to the slots 20 of the member A.

The friction device proper may be of suit-

able form, the one illustrated comprising a pressure-transmitting wedge 21, wedge friction shoes 22 and 23, a preliminary spring 24, main spring follower 25, twin arranged main springs 26-26, and another spring follower 27, the latter bearing against the key D. The gear proper is maintained of desired over-all length by a bolt 28 having shouldered engagement with the spring follower 25 at one end and with the wedge 21 at the other end. A rear main follower 29 is employed, the same normally engaging the rear stops 16.

The member A, as shown, is in the form of an integral casting having a top wall 30, bottom wall 31, and side walls 32-32, and an intermediate partition 33.

The top wall 30 is substantially horizontal throughout the entire length of the member A and, at its front end, is provided with an upstanding flange 34 which abuts the usual horn of the coupler. The bottom wall 31 is also substantially horizontal throughout its entire length and extends forwardly to a point in line with the coupler horn. At the rear end of the member A, as best shown in Fig. 1, the top and bottom walls 30 and 31 are made of reduced width, as indicated at 35-35, and are connected by a vertical section 36 so as to provide a short loop section at the rear end of the member A within which is received the follower 29.

The side walls 32, forwardly of the partition 33, extend parallel as indicated at 133 and then flare outwardly as indicated at 233, to allow for the usual lateral motion of the coupler when rounding curves. Rearwardly of the partition 33, the side walls 32 diverge as indicated at 333 until the full width of the spring cage and friction shell proper is reached and then said side walls extend parallel, as indicated at 433, to the open end of the shell. The member A, and contained parts, is held in proper position by a carry iron 37 and saddle plate 38.

Referring to Fig. 1, it will be seen that the top and bottom walls of the member A are provided with vertically disposed, narrow, transversely extending flanges 138-138 which provide shoulders for the follower 27 and at the same time leave a recess or opening for a forwardly extending thick rib 39 on the follower 27 which rib has a rounded recess 40 fitting the rear edge of the key D.

In a buff action, it is evident that the butt end of the coupler B bears against the partition 33 and hence will produce simultaneous and corresponding movement of the member A. As the friction shell portion thereof moves rearwardly, the desired friction action is set up, inasmuch as the wedge 21 is held against rearward movement by the follower 29 which, in turn abuts the stops 16. This buff movement will preferably approximate 5" to 6", it being noted that ample provision

for this movement is provided by the elongated key slots 17 and 19. The buff movement will preferably be limited by the keys C and D simultaneously engaging the rear ends of the slots 17 and 19 and by the member A engaging the follower 29. Should there be an excessive buff shock that is not fully absorbed by the gear, the over-load will be taken by the flange 34 engaging the buffer casting, as will be understood. In a draft action, the key D remains stationary and the member A will be pulled forwardly by the coupler B through the key C. It will also be observed that the yoke section 35-36 of the member A will move forwardly simultaneously and consequently there will be no friction action since there will be no relative movement produced between the shell proper and the friction shoes. However, the forward movement of the member A and associated friction elements will compress the springs 26, the forward ends of which are held stationary by the follower 27 which bears on the key D. The draft action will preferably be confined to about 2½" to 3" and will be determined by the length of the slots 20 in the member A, the rear edges of said slots engaging the key D at the limit of the draft movement.

From the preceding description, it will be seen that I have provided a draft gear of simple and economical form having capacity for absorbing exceedingly heavy shocks in buff and having the necessary easier cushioning action in draft without any increase in train slack.

Although I have herein shown and described what I now consider the preferred manner of carrying out my invention, the same is merely illustrative and I contemplate all changes and modifications that come within the scope of the claims appended hereto.

I claim:

1. In a railway draft rigging, the combination with draft sills; of a combined yoke and friction shell member movable relatively to said sills; friction elements cooperable with said shell member; spring means cooperable with said friction elements; means causing relative movement between said friction elements and shell when the latter is moved in one direction lengthwise with respect to the sills; and means for moving said friction elements in unison with said shell when the latter is moved in the opposite direction lengthwise of the sills.

2. In a draft rigging, the combination with draft sills; of a combined yoke and friction shell member; front stop acting means relative to which said member is movable in draft; rear stop acting means; friction elements cooperable with said shell and said rear stop acting means; and spring means interposed between said friction elements and front stop acting means whereby in buff, a

spring friction action is obtained, and, in draft, a spring action only.

3. As an article of manufacture, a single-piece yoke and shell member having top, bottom and side walls, said member being open at opposite ends, one of said open ends being adapted to receive a coupler shank, said member having a fixed intermediate partition forming an abutment for the inner end of the coupler shank, and an integrally formed loop at the other end of said member overhanging the opening at said end.

4. In a draft rigging for cars, the combination with draft sills fixed to the car; of front and rear stop-acting means fixed to the sills; a combined friction shell and spring cage and associated spring means and friction elements; a follower cooperable with said spring means and movable relatively to said shell and spring cage in one direction, said follower cooperating with certain of said stop-acting means to hold the follower against movement with respect to the car, in an opposite direction; means for moving said shell and cage and elements associated therewith as a unit toward said follower when so held; and additional follower means movable in unison with the shell in said last-named direction for compressing the spring means against the first-named follower, whereby a spring resistance only is obtained during said movement, said shell being movable relatively to the friction elements and additional follower in an opposite direction.

35 5. In a draft rigging, the combination with draft sills having rear stop-acting means; of a combined yoke and friction shell member movable in unison with a coupler in both buff and draft; spring means and friction elements associated with the shell, said spring means opposing movement of the elements inwardly of the shell; a follower interposed between said friction elements and rear stop-acting means and held against movement by said stop-acting means during a buff action; a second follower held against movement in draft, on which follower said spring means bears; and means movable in unison with the shell in draft action for compressing the spring means against said last-named follower.

In witness that I claim the foregoing I have hereunto subscribed my name this 7th day of February, 1928.

WILLIAM A. GEIGER.
